US00D871033S

(12) **United States Design Patent** (10) **Patent No.:** **US D871,033 S**
(45) **Date of Patent:** **** Dec. 31, 2019**

(54) **SOLE**

- (71) Applicant: **Reebok International Limited**, London (GB)
- (72) Inventor: **Ilija Nikolic**, Stoughton, MA (US)
- (73) Assignee: **Reebok International Limited**, London (GB)
- (**) Term: **15 Years**
- (21) Appl. No.: **29/676,070**

(22) Filed: **Jan. 8, 2019**

Related U.S. Application Data

(63) Continuation of application No. 29/612,112, filed on Jul. 28, 2017, now Pat. No. Des. 841,299.

(51) **LOC (12) Cl.** **02-04**

(52) **U.S. Cl.**

USPC **D2/947**; D2/957; D2/959

(58) **Field of Classification Search**

USPC ..... D2/902, 906, 908, 916, 918, 925, D2/946–962, 977; 36/1, 1.5, 3 B, 22 R, 36/24.5, 25 R, 28, 32 R, 34 R, 59 C, 36/67 A, 101–107, 114–116, 117.3, 117.4, 36/124–136; D12/544

CPC A43B 13/00; A43B 13/02; A43B 13/023; A43B 13/026; A43B 13/04; A43B 13/08; A43B 13/10; A43B 13/12; A43B 13/14; A43B 13/141; A43B 13/143; A43B 13/16; A43B 13/18; A43B 13/181; A43B 13/187; A43B 13/189; A43B 13/20; A43B 13/22; A43B 13/223; A43B 13/24; A43B 13/28; A43B 13/30; A43B 13/32; A43B 13/34; A43B 13/36

(57) **CLAIM**

The ornamental design for a sole, as shown and described.

DESCRIPTION

FIG. 1 is a front side perspective view of a sole showing the claimed design;

FIG. 2 is a rear side perspective view thereof; and, FIG. 3 is a side view thereof.

The dashed broken lines in the figures show portions of the sole that form no part of the claimed design.

The dot-dash broken lines in the figures show boundaries that form no part of the claimed design.

1 Claim, 3 Drawing Sheets
